UNITED STATES PATENT OFFICE

163,696

ROTARY MOWER HOUSING

William H. Huff, Kansas City, Kans., assignor to
Propulsion Engine Corporation, Kansas City,
Kans., a corporation of Missouri

Application March 20, 1950, Serial No. 8,651

Term of patent 3½ years

(Cl. D40—1)

To all whom it may concern:

Be it known that I, William H. Huff, a citizen of the United States, residing at Kansas City, in the county of Wyandotte and State of Kansas, have invented a new, original, and ornamental Design for a Rotary Mower Housing, of which the following is a specification, reference being had to the accompanying drawing, forming a part thereof.

Fig. 1 is a top plan view of a rotary mower housing, showing my new design.

Fig. 2 is a side elevational view thereof.

Fig. 3 is a rear end view.

Fig. 4 is an inverted plan view.

Fig. 5 is a side elevational view opposite to that shown in Fig. 2; and

Fig. 6 is a front end elevational view.

I claim:

The ornamental design for a rotary mower housing, as shown.

WILLIAM H. HUFF.
